United States Patent Office.

GEORGE BUSHNELL, OF SCHODACK, NEW YORK.

Letters Patent No. 69,401, dated October 1, 1867; antedated September 26, 1867.

IMPROVEMENT IN BELLows.

The Schedule referred to in these Letters Patent and making part of the same.

TO ALL WHOM IT MAY CONCERN:

Be it known that I, GEORGE BUSHNELL, of the town of Schodack, in the county of Rensselaer, and State of New York, have invented a certain new and useful Improvement in Bellows for propelling or compressing air or gases useful for illuminating apparatus and other purposes; and I do hereby declare that the following is a full, clear, and exact description thereof, reference being had to the accompanying drawing, and the letters of reference marked thereon.

The nature of my invention consists in arranging a series of single bellows between two disks, and, by imparting a peculiar motion to the lower disk by means of a rotating wheel and rod operated thereby, alternately distend and compress the several bellows in regular succession, and may be fully understood by the following detailed description.

Figure 1 represents a plan of this invention,

Figure 2 a plan of the lower board of the bellows,

Figure 3 an elevation, and

Figure 4 a vertical section.

The same letters of reference apply to the same parts in the several figures.

A is the upper board of a square reservoir bellows, B the lower board, and C the flexible rim thereof. D is the upper board of the several small or feeding bellows E. In this board D are valves G, opening upwards each from the several small bellows E into the chamber F. The several bellows E have one bottom board, H, in common, in which are valves I, opening upwards, but are each provided with separate and distinct flexible sides or diaphragms K, so that each small bellows is a separate and distinct chamber or compartment. The lower board H is rigidly secured to a shaft or rod, L, held at the upper end by a universal joint, M, and at the lower end secured in an eccentric position to a rotating wheel, N, from which it receives such a motion that the axis of the rod L describes a cone, the apex of which is in the centre of the universal joint.

The action of the lower board of the smaller bellows is to successively expand and contract the several bellows E E, &c., and these several bellows, receiving air by their lower valves when contracting into the chamber F, from which chamber through the valve O into the upper bellows or reservoir. When this upper bellows is inflated, the valve O is closed by means of the lever P, operated by the cord Q, attached to and operated by the board A, the valve O being an ordinary clack valve and free to open upward whenever the pressure below exceeds that above and the weight of the valve, until the upper bellows becomes sufficiently inflated, when the lever P, operated by the cord Q, connecting one arm of the lever to the board A, effectually closes the valve, and holds it so until the upper bellows has been partially emptied of its contents and the board A has descended. The moment of closing of the valve O is under control by reason of the cord Q being adjustable in its length. Undue pressure in the upper bellows, or the vessels or tubes leading from it, is thus rendered impossible.

What I claim as my invention, and desire to secure as such by Letters Patent, is—

1. The combination of the several smaller bellows with the rod L, operating substantially in the manner hereinbefore described.
2. The combination of the bellows E with the chamber F, valve O, and lever P, as hereinbefore set forth and described.
